UNITED STATES PATENT OFFICE.

NUNEZ CLARENCE FERRIS, OF BROOKLYN, NEW YORK, ASSIGNOR TO ELIZABETH F. BOYLE, OF BROOKLYN, NEW YORK.

APPARATUS FOR TREATING MUSIC SHEETS.

Application filed July 17, 1919. Serial No. 311,469.

To all whom it may concern:

Be it known that I, NUNEZ CLARENCE FERRIS, a citizen of the United States, residing in the city of New York, borough of Brooklyn, in the county of Kings and State of New York, have invented a certain new and useful Improvement in Apparatus for Treating Music Sheets, of which the following is a specification.

10 The invention relates to apparatus for treating music sheets, and the object of the invention is to provide simple, easily operated, power-driven mechanism for rotating a plurality of spools and guiding the sheets thereto, whereby a number of sheets may be spooled simultaneously by a single operator.

20 A further object is to provide means for loosening and removing any punchings or other particles or shreds adhering to the sheets, during the spooling operation, and for printing the expression lines on such sheets during such operation.

25 Another important object is to provide means whereby the operator may turn any of the spools in advance in initiating the winding operation, independently of the other spools.

30 The invention consists in certain novel features of construction and arrangement by which the above and other objects are attained, to be hereinafter described and claimed.

35 The accompanying drawings form a part of this specification and show the invention as it has been carried out in practice.

Figure 1 is a front elevation of the apparatus.

40 Figure 2 is a corresponding vertical section, taken transversely of the apparatus on the line 2-2 in Figure 1, and partly in elevation.

45 Figure 3 is a plan view on a larger scale, showing an end portion of a plate forming the table-top and serving to guide the sheets.

Figure 4 is a corresponding edge or front view.

50 Figure 5 is front elevation showing one of the driven devices for holding the spool during the winding operation.

Figure 6 is an end view of the same.

55 Figure 7 is a front elevation of one of the driving sprocket-wheels and its clutch, for rotating the driven device shown in Figures 5 and 6.

Figure 8 is a face view of such driving sprocket-wheel and clutch.

Figure 9 is a side view of a master tracing wheel for controlling the marking wheels for printing the expression line.

60 Figure 10 is an elevation showing one end of a vacuum bar for removing punchings and shreds.

Figure 11 is a corresponding vertical transverse section.

65 Similar letters of reference indicate the same parts in all the figures.

A A are uprights or legs supporting a table A¹ on which is a plate B of sheet metal forming the upper face of the table and having transverse flanges or ribs B¹ arranged in pairs, spaced apart a distance corresponding substantially to the width of a music sheet received between such pairs, and guide such sheet smoothly across the table to the 75 spool. The table as shown in Figure 1, is equipped for five sheets one of which, at the centre, may be a master-sheet.

On the rear of the table is a horizontally disposed rack C having bars C¹ on which 80 the music sheets M are hung in loops as indicated in dotted lines in Figure 2, in position to be drawn therefrom across the table to the spools. The latter, only one of which is shown, marked N in Figure 1, are 85 received in holders mounted on a vertical front board A² adjacent the table top. Each holder consists of a bracket D having a hollow head D¹ in which is mounted a bar or slide D² having its outer end rounded to 90 match to a corresponding recess, not shown, in one end of the spool, and its inner end abutting against a helical spring D³ within the head. A pin D⁴ extending radially from the slide is received in a longitudinal slot d 95 in the head and serves to limit the axial movement of the slide and prevent its withdrawal.

In the head D¹ opposite to the slide, is fixed a stud D⁵ having a head D⁶, on which 100 stud is loosely mounted a sprocket-wheel D⁷ having on its outer face a bridge D⁸ extending over the head D⁶ of the stud and equipped with a transverse rib D⁹ adapted to engage in the usual notch or slit, not shown, in the 105 opposite end of a spool N.

The spools are inserted by engaging the rounded slide D² in one end and by forcing the slide inwardly against its spring engaging the slit at the other end of the spool 110

with the rib D⁹ of the next bracket D, and the brackets are so disposed relatively to each other and to the sheet-channels on the plate B, as to present the spools in exact 5 alignment with such channels and sheets.

The spools are rotated in the direction to wind the sheets thereon by sprocket chains F¹ running on the sprocket-wheels D⁷ from sprocket-wheel F² loosely mounted on a shaft 10 F extending along the front of the apparatus and supported in bearings A⁸ on a shelf A⁴ below the level of the table. Each sprocket-wheel F² is held between collars F³ F⁴ fixed on the shaft, and the collar F³ carries ratchet teeth F⁵ engaged by a pawl F⁶ on the sprocket-wheel F² held in yielding engagement by a spring F⁷.

The shaft F is revolved by a belt, not shown, running on a pulley F⁸ from any 20 suitable motor, not shown, controlled by the operator.

The sheets are hung on the racks C with the ends lying in the channels on the plate B and are attached at their ends to the cores 25 of the spools by the attendant; the ratchet and pawl permits the operator to rotate the spools independently by hand in the winding direction for the required number of turns to insure engagement, and the shaft F is 30 then rotated, imparting motion through the sprocket-wheels and chains to the spools, thus drawing the sheets from the racks, exposing them for inspection during their 35 passage across the table on which they are guided by the ridges or ribs B¹, and winding them smoothly upon the spools.

By forming the table top of the metal plate B, a plane smooth surface is obtained 40 capable of withstanding the wear of the sheets, and not liable to become warped or otherwise changed by atmospheric conditions of heat and moisture.

G is a shaft mounted in uprights A¹⁰ above the table at the rear, driven by a belt 45 E from a pulley E¹ on the shaft F to a pulley E². Loosely hung on the shaft G is a series of depending links G¹ in which is mounted a shaft G² provided with cylindrical brushes G³ located to match each to a sheet in its 50 traverse from the rack to the table top. The brush shaft G² is rotated by a sprocket chain G⁴ at one end, running on sprocket-wheels G⁵ and G⁶ on the shafts G and G² respectively.

55 The shaft G² with the links G¹ forms a suspending frame which may be swung to bring the brushes G³ into wiping contact with the surface of the sheets and thus loosen and brush away any disks of paper not wholly detached or removed in the perforating process, or other shreds of paper or other foreign matter adhering to the surface of the sheet. The brushes are swung 60 through the medium of a lever G⁷ fixed to a short shaft G⁷⁰ and connected by a link G⁸

with the link G', as seen clearly in Figure 2. The attendant can readily swing the brushes when desired by a hand lever applied to the shaft G⁷⁰. Such handle is seen at G¹¹ in Figure 1.

70 On the front edge of the table is a series of strips or members H, over the upper edges of which the sheets pass in their traverse from the table to the spools. Each member is hollow, having a longitudinal cavity h therein and a narrow slit or mouth h¹ extending along its upper edge, and H¹ is a pipe leading from the interior of the member to any suitable air pump, not shown, adapted to maintain a partial vacuum in the 80 cavity h and cause any particles of dust or shreds of paper in the perforations of the sheet to be drawn therefrom by suction and thus free the sheet from matter liable to enter the tracker-board apertures of a 85 playing mechanism with which the sheet is to serve.

J is a shaft extending longitudinally beneath the table and suspended from the latter by hangers A¹¹ A¹¹. It carries a lever 90 of bell-crank form, the horizontal arm J¹ of which carries a horizontally disposed rod J¹⁰, see Figure 2 on which are pivoted the lower ends of vertical rods J² J² extending 95 through the table A and plate B between adjacent pairs of ribs B¹, and each carries at its upper end a yoke J³ equipped with a pair of separated horizontal transverse rollers J⁴ J⁴ serving as anti-friction guides for a bar L 100 loosely mounted in the yokes and arranged to be reciprocated by the hand of the attendant longitudinally of the table and above the latter.

In the bar L and over each sheet channel 105 is loosely mounted a short vertical shaft or pintle L¹ held to the bar by collars L² above and below the bar, and free to rotate in the latter while moving therewith. Each pintle carries at the lower end a bifurcated arm L³ 110 in which is mounted a circular disk or wheel.

The wheels L⁴ L⁴ of the series, on each side of the centre are provided with inking rollers L⁵ mounted on the arms L³, and are adapted to print each an expression line on the sheet passing beneath it when lowered thereon. The central wheel L⁶ of the series 115 is shown as not equipped with an ink roller and is intended to be guided along the expression line on the central master-sheet and thus cause the printing or marking wheels L⁴ to produce corresponding lines on their sheets.

The bar L and its wheels and rollers are held suspended above the table during the introduction of the sheets and are lowered 120 during the winding operation. These rising and sinking movements are effected through the bell crank lever arm J¹ which is connected through a rod J⁵ to a foot lever J⁶ pivotally mounted in a portion A¹² of the 130

frame at the midlength of the apparatus. By depressing the outer end of the foot lever the rods J^2 and their connections will be raised, and on releasing the foot lever, will 5 be lowered by gravity.

In order to hold the rods J^2 in the elevated position during the introduction of the sheets, a swinging arm K is hinged to the table frame, carrying on its under face a 10 beveled nose K^1 adapted to engage a pin J^8 on the vertical arm J^7 of the bell-crank. A rod K^2 pivoted at the upper end to the arm K extends downwardly to a foot lever K^3 by which the arm K can be raised. 15 To lower the series of wheels L^4 and L^5 the outer end of the foot lever K^3 is depressed, correspondingly raising the arm K and withdrawing the nose K^1 from engagement with the pin J^8 . Thus released, the 20 rods J^2 and their equipment sink by gravity until supported by the wheels L^4 and L^5 upon the sheets. The attendant then grasps the bar L and moves it in the yokes J^3 to cause the central wheel L^6 to follow the expression line on the master sheet as the latter traverses across the table, and in doing 25 so causes the printing wheels L^4 to describe similar parallel paths on the other sheets and mark corresponding expression lines there- 30 on.

The bar L and its connections are then raised by depressing the foot lever J^6 . The pin J^8 on the lever arm J^7 automatically lifts the arm K , rides under the beveled nose 35 K^1 and is engaged by the latter and thus held in the elevated position until again lowered.

At the completion of the winding operation the revolution of the shaft F may be 40 stopped in any desired or well-known way, for instance, by means of a brake of which R is the operating lever after first throwing off the belt from the pulley F^8 .

S S are idle sprocket-wheels mounted on 45 the board A^2 and engaging the sprocket chains F^1 to induce the desired tension in the latter by taking up any slack.

The rack C is shown as hinged to the frame at c and supported by cords or wires 50 C^2 so as to be folded to the frame when not in use.

The marking wheels L^4 and the central wheel L^6 are mounted in arms L^3 all of the same length and distance from the pintles 55 L' so that all swing under the same conditions. All the wheels rest on sheets traveling at the same rate of speed and the effect of moving the bar L in either direction is to swing all the arms L^3 in unison and with 60 the central wheel L^6 and to the same extent, and hence all the sheets are marked to correspond to the master sheet and to each other.

Modifications may be made in the forms 65 and proportions of the apparatus without

departing from the principle of the invention, and parts may be used without the whole. The apparatus may be constructed to treat a greater or less number of sheets than here shown.

70

I claim:

1. In an apparatus of the character set forth, a table, means for supporting a plurality of music sheets in position for presentation thereto in the same horizontal plane, 75 spooling mechanism for such sheets, means for guiding such sheets separately and independently of each other across said table from said supporting means to said spooling mechanism, a series of marking wheels 80 above said table, and means for moving said printing wheels simultaneously into and out of contact with such sheets in the traverse of the latter.

2. In an apparatus of the character set forth, a table, means for supporting a plurality of music sheets in position for presentation thereto in the same horizontal plane, 85 spooling mechanism for such sheets, means for guiding such sheets separately and independently of each other across said table from said supporting means to said spooling mechanism, a series of marking wheels above said table, means for moving said marking wheels simultaneously into and out of contact with such sheets in the traverse of the latter, and means embodying said last-named means for moving said printing wheels transversely of such sheets.

3. In an apparatus of the character set forth, a table, means for supporting a plurality of music sheets in position for presentation thereto, spooling mechanism for such sheets, means for guiding such sheets across said table from said supporting means to 105 said spooling mechanism, a bar movable transversely of such sheets, a series of marking wheels mounted on said bar above the sheets, and means for raising and lowering said bar.

4. In an apparatus of the character set forth, a table, rods extending vertically through said table, yokes on the upper ends of said rods, a bar carried by said yokes and movable longitudinally therein, a series of 115 marking wheels mounted on said bar above the sheets, and means for raising and lowering said bar.

5. In an apparatus of the character set forth, a table, rods extending vertically 120 through said table, yokes on the upper ends of said rods, a bar carried by said yokes and movable longitudinally therein, a series of marking wheels mounted on said bar above the sheets, means for raising said rods and 125 for locking them in the elevated position, and means for unlocking said rods and permitting the latter and said bar and marking wheels to descend by gravity.

6. In an apparatus of the character set 130

forth, a table, rods extending vertically through said table, yokes on the upper ends of said rods, a bar carried by said yokes and movable longitudinally therein, a series of 5 marking wheels mounted on said bar above the sheets, means operated by a foot lever for raising said rods and for locking them in

the elevated position, and means actuated by a foot lever for unlocking said rods and permitting the latter and said bar and marking wheels to descend by gravity. 10

In testimony that I claim the invention above set forth I affix my signature.

NUNEZ CLARENCE FERRIS.
